UNITED STATES PATENT OFFICE.

JULIUS A. FLESCII, OF CHICAGO, ILLINOIS.

DESIGN FOR A COOLER OR REFRIGERATOR.

SPECIFICATION forming part of Design No. 23,179, dated April 10, 1894.

Application filed February 8, 1894. Serial No. 499,542. Term of patent 7 years.

To all whom it may concern:

Be it known that I, JULIUS A. FLESCH, a citizen of the United States, residing at Chicago, in the county of Cook and State of Illinois, have invented and produced a new and original Design for Coolers or Refrigerators, of which the following is a full, clear, and exact specification, reference being had to the accompanying drawing, showing a part thereof.

The said drawing is a perspective view of the cooler or refrigerator, showing my design.

The leading feature of my design consists of a box-like structure having plates set in its upper side at a distance apart, and apparently constituting the walls of two compartments, A, B. The compartments, A, B, are arranged one at each of the upper corners of the box-like structure and at its ends, and the plates which constitute the walls of these compartments on the broad side of the structure or cooler are set in frames, a, which give the appearance of doors having knobs or latches, b, the other of such plates, C, C', which constitute the ends and tops respectively of the compartments A, B, being merely surrounded by the corners of the structure, or woodwork.

The top of the cooler or structure is substantially flat, and the top glasses, C', set therein, are also flat, and arranged substantially flush or on a level with the edges of the

cooler, and also flush with the intervening portion D, so as to be in substantially the same plane with the latter, whereby the top 35 of the cooler will be flat from end to end, and have the appearance of a counter or show-case.

Between the compartments A, B, is located a door, E, which apparently closes the entrance to a third compartment, and below this 40 door, in the body of the box or cooler, is another door, F, which is seemingly the entrance to another compartment, and on either side of the door F are ranged other doors, G, which appear to open into yet other compartments, 45 one of which is below each of the compartments, A, B. The upper side of each of the doors, F, G, is ornamented with a longitudinal panel, while on the lower side of each appears a pair of upright panels, and a pair of 50 these upright panels is also arranged on the door E, above the horizontal panel on the door F. An arrangement of panels similar to that on the doors also appears at the end of the box, below the plate, C. 55

Having thus described my design, what I claim, and desire to secure by Letters Patent, is—

The design for coolers or refrigerators, substantially as herein shown and described.

JULIUS A. FLESCH.
